SUPPORT

Paul M. Hassler, Batavia, Ill., assignor to
 Richards-Wilcox Manufacturing Company,
 Aurora, Ill., a corporation of Illinois

Application March 16, 1938, Serial No. 196,141

4 Claims. (Cl. 191—42)

This invention relates to supports for electric conductors employed to supply current to electric hoists operating on trolley tracks and other installations where it is desired to supply current to a moving device.

One of the principal features of this invention resides in the provision of a conductor support which includes a threaded member that embraces opposite sides of the conductor and receives an insulator having a threaded socket, the parts being so constructed and arranged that when the insulator is screwed down on the threaded portion of said conductor embracing member, the socket of the insulator embraces side portions of said member and forces them laterally inwardly against the conductor so as to hold the same rigidly against movement.

A further feature of this invention resides in the provision of a conductor engaging member that has hinged or resiliently connected conductor engaging sections arranged for relative movement and clamped against the track by a camming or wedging action which is exerted against the sections by the insulator.

These and other objects and advantages of the present invention will be apparent to those skilled in the art after a consideration of the following detailed description taken in conjunction with the accompanying drawing.

In the drawing:

Figure 1 is a generally vertical section taken through a conductor supporting structure embodying the principles of this invention;

Figure 2 is a side view, on a reduced scale, of the construction shown in Figure 1;

Figure 3 is a modified form of the present invention in which one of the conductor engaging sections is hinged to the other; and

Figure 4 illustrates a construction in which both of the conductor engaging sections are hinged to the threaded member which is received and supported by the insulator in such relation that the latter clamps both of the conductor engaging sections against the conductor.

Referring now more particularly to Figure 1, the reference numeral 1 indicates an electrical conductor in the form of a rail of what is termed figure-8 configuration, having a supporting section 2 and a contact section 3. Conductor rails of this kind are well known in the art and are used for conducting current to the current collectors or contacts of movable devices, such as electric hoists operating on trolley tracks, and the like. The trolley rail or conductor 1 is usually carried by insulators 5 fastened to suitable sup-

porting members, one of which is shown at 6 in the form of a structural angle, and each insulator 5 has a head 8 formed of dielectric material and having a horizontal groove 9 to receive the yoke of a U-bolt 11 the threaded ends 5 of which pass through suitable openings in the vertical flange of the angle bar 6 and receive nuts 12 by which the insulator is clamped firmly to its support.

According to the principles of this invention, the insulator is provided with an interior sleeve or socket 15, which is embedded in the insulator head when the latter is molded or otherwise formed. The neck portion 16 of the sleeve is threaded, as at 17, and below the neck portion 15 the sleeve has a skirt portion 18 which tapers outwardly and downwardly to the lower part of the insulator.

A conductor clamping and supporting member 22 has a threaded stem 23 that screws into the portion 17 of the socket. The lower end of the member 22 is slotted, as at 25, so as to form two oppositely disposed sections 27 and 28 which at their lower ends have recesses 29 formed to engage opposite sides of the supporting section 25 of the conductor rail 1. By virtue of the slotted construction the sections 27 and 28 are resilient at the point of juncture where they join the threaded stem 23. The outer portions of the sections 27 and 28 are extended to form outwardly angled camming edges or surfaces so that when the insulator is screwed down tight on the member 22 the skirt section of the socket 16 engages the sections 27 and 28 and forces them inwardly with a wedging or clamping action against the rail 1, thus clamping the latter at two places.

The engagement of the recesses 29 about the rail head 2 holds the rail up in position and the clamping action of the sections prevents the rail from slipping endwise. It will also be noted that the sections 27 and 28 engage the rail 1 on opposite sides of the web 4 so that there is no likelihood of the rail being twisted laterally in the insulator. It will also be noted that there is no clamping action against the upper edge 40 of the rail that mars or deforms the same, as might occur where set screws and the like are used.

Figure 3 shows a modified form of the present invention in which the conductor clamping member is of hinged construction instead of being resilient. Usually it is preferable to apply the member 22 of Figure 1 by slipping the same over the rail from one end, but if a hinged member, such as is indicated at 22a in Figure 3,

is used it is possible to apply the same directly over the rail from one edge.

The member 22a includes a part 35 which is threaded at its upper end, as at 36, and at its lower end is formed with an extension 37 having a rail-receiving recess 39. A recess or groove 41 is formed between the threaded stem 36 and the extension 37, and a shoulder 42 is formed just below the recess 41.

10 A part 45 has a rounded projection 46 that is adapted to seat in the recess 41, and the part 45 is formed with a conductor receiving recess 47 which is directly opposite the recess 39 when the part 45 is in position. By virtue of the 15 rounded portions 41 and 46 at the point of juncture between the jaw parts 35, 45 and the threaded shank 36, the part 45 can pivot or hinge with respect to the other part 35. The two parts or sections 35 and 45 of the member 22a are 20 shaped so that they are engaged and forced with a camming or wedging action inwardly toward one another by the skirt portion 48 of sleeve 15 when the insulator is screwed down tight.

Figure 4 illustrates another modified form in 25 which the principles of the present invention are embodied and differs from the form shown in Figure 3 in that the latter has only one conductor engaging section hinged, the other being formed integrally but with a certain amount of 30 resilience adjacent the recess 41 with the threaded shank, whereas in Figure 4, both of the conductor engaging sections are hinged to the threaded section.

Referring now to Figure 4, the reference numeral 22b indicates the conductor supporting member in its entirety which is adapted to be supported by an insulator 5 and arm or bar 6 in the manner described above. The conductor supporting member 22b comprises a threaded 40 stem 51 carrying head 52 at its lower end in which oppositely disposed recesses 53 and 54 are formed. A pair of conductor engaging sections 55 and 56, which may be identical, are provided, and each is formed with a recess 57 to receive 45 the rail head 2, and at the opposite end of each of the members 55 and 56 a rounded or nose portion 58 is formed. These nose sections are adapted to be disposed in the recesses 53 and 54, thereby forming a pivotal point of juncture between the jaw sections 55, 56 and the threaded shank 51, so that when the insulator 5 is screwed 50 down on the threaded stem 51, the sections 55 and 56 pivot in the recesses 53 and 54 and are cammed or wedged toward one another so as to 55 clamp the conductor 1 firmly therebetween.

It is to be understood that while I have shown and described above the preferred means in which the principles of the present invention have been embodied, my invention is not to be limited to the specific details shown and described above, but that, in fact, widely different means may be employed in carrying out the broader aspects of my invention.

What I claim, therefore, and desire to secure 60 by Letters Patent is:

1. A conductor support comprising a member having a threaded shank at one end and a conductor receiving section at the other end with a recess between said shank and said section, a 65 companion section adapted to receive one side of a conductor and having a projection adapted to be seated in said recess so that one section can move with respect to the other to provide for the insertion of a conductor therebetween, 70 and an insulator having a socket adapted to be

screwed onto said threaded shank and a portion embracing said sections, said portion and said sections being formed so that the latter are forced laterally inwardly to clamp a conductor therebetween when said insulator is screwed onto said 5 threaded shank.

2. In a support for a conductor rail of figure-8 cross section having cylindrical upper and lower portions and a substantially flat intermediate web portion, the combination of gripping means 10 for gripping said conductor rail comprising a threaded shank and two jaw sections, the lower portions of said jaw sections having opposing faces for engaging the sides of said flat intermediate web portion of the rail, said opposing 15 faces having recesses therein for engaging over the cylindrical upper portion of the rail, the upper portions of said jaw sections having a juncture with each other and with said threaded shank such that one of said jaw sections can move laterally toward and from the other jaw section, said jaw sections having outer cam surfaces extending on a very gradual taper outwardly and downwardly from the point of juncture of said 20 jaw sections with each other and with said 25 threaded shank, a metallic sleeve extending down over said rail gripping means, said sleeve having a threaded socket in its upper end for screwing down over said threaded shank, said sleeve comprising a long gradually tapered skirt portion 30 for engaging the cam surfaces of said jaw sections, said skirt portion engaging said cam surfaces at points considerably below the point of juncture of said jaw sections with each other and with said threaded shank, whereby a major 35 component of the force exerted downwardly by said skirt portion against said cam surfaces is effective horizontally as a gripping force acting against the sides of the conductor rail, a unitary hood of insulation enshrouding the top and sides 40 of said metallic sleeve, said metallic sleeve comprising surfaces which are embedded in said insulating hood and which prevent relative rotation and axial separation between said sleeve and said hood, said hood having an annular 45 groove therein, and a U-shaped supporting clamp to a fixed point of support.

3. In a support for a conductor, the combination of gripping means for gripping said conductor comprising a threaded shank and two jaw sections, the lower portions of said jaw sections having opposing faces for engaging the sides of the conductor, the upper portions of said jaw sections having a juncture with each other and 55 with said threaded shank such that one of said jaw sections can move laterally toward and from the other jaw section, said jaw sections having outer cam surfaces extending on a very gradual taper outwardly and downwardly from the point 60 of juncture of said jaw sections with each other and with said threaded shank, a metallic sleeve extending down over said conductor gripping means, said sleeve having a threaded socket in its upper end for screwing down over said 65 threaded shank, said sleeve comprising a long gradually tapered skirt portion for engaging the cam surfaces of said jaw sections, said skirt portion engaging said cam surfaces at points considerably below the point of juncture of said jaw sections with each other and with said threaded shank, whereby a large component of the force 70 exerted downwardly by said skirt portion against said cam surfaces is effective horizontally as a gripping force acting against the sides of the 75

conductor, a unitary hood of insulation enshrouding the top and sides of said metallic sleeve, said metallic sleeve comprising surfaces which are embedded in said insulating hood and which prevent relative rotation and axial separation between said sleeve and said hood, and means for attaching said insulating hood to a fixed portion of support.

5. In a conductor support, the combination of gripping means comprising a threaded shank and two conductor receiving sections, said conductor receiving sections adapted to receive opposite sides of a conductor, said threaded shank having a recess formed therein, one of said conductor

receiving sections having a projection adapted to be seated in said recess so that said latter conductor receiving section can move with respect to the other conductor receiving section to provide for the insertion of a conductor therebetween, and an insulator having a socket adapted to be screwed onto said threaded shank and a portion embracing said conductor receiving sections, said portion and said sections being formed so that the latter are forced laterally inwardly 10 to clamp a conductor therebetween when said insulator is screwed onto said threaded shank.
